UNITED STATES PATENT OFFICE.

ABRAHAM L. MACMASTER, OF CHICAGO, ILLINOIS, ASSIGNOR TO JACOB C. LE BOSKY AND JESSE COX, OF SAME PLACE.

LOCK.

SPECIFICATION forming part of Letters Patent No. 658,955, dated October 2, 1900.

Application filed June 15, 1899. Serial No. 720,720. (No model.)

To all whom it may concern:

Be it known that I, ABRAHAM L. MACMASTER, a citizen of the United States, residing in the city of Chicago, in the county of Cook 5 and State of Illinois, have invented a new and useful Improvement in Locks, of which the following is a specification.

My invention relates to improvements in locks operated by keys; and the objects of my 10 invention are, first, to provide means for preventing the operation of the lock by false keys; second, to provide means whereby the bolt when cast is firmly held in position and cannot be moved by force exerted directly on 15 said bolt; third, to provide a key of such construction that it will be substantially unaffected by wear, and, fourth, to provide the other details hereinafter set forth. I attain these objects by the mechanism illustrated in 20 the accompanying drawings, in which—

Figures 1 and 2 are side views of a padlock embodying my invention, the side plate being removed to show the working parts. In Fig. 1 the bow is down and the bolt is shot 25 or cast. In Fig. 2 the bow is up and the bolt is retracted. Fig. 3 is a top view of a bolt-lock embodying my invention, the top plate or cover being removed to show the working parts. Fig. 4 is a diagrammatic side view of 30 the cylindrical portion of a segment rectified and showing various possible forms and arrangements of the teeth or pins. Fig. 5 shows a key adapted to operate my form of lock. Fig. 6 is a view of the lower side or face of a 35 portion of the bolt adapted for use in the form of lock shown in Figs. 3, 8, and 9. Fig. 6 also shows the auxiliary slide whereby the bolt may be released from the actuating-segment. Fig. 7 is a face view of the auxiliary slide 40 adapted for use in the form of bolt shown in Figs. 3, 6, 8, and 9. Fig. 8 is a top view of the form of lock shown in Fig. 3. The bolt is shown retracted by means of the bolt-actuating segment. Fig. 9 is a top view of the 45 form of lock shown in Figs. 3 and 8. The bolt is shown retracted by means of the bolt-spindle.

Similar letters refer to similar parts throughout the several views.

50 I will first describe my invention as applied to a padlock, Figs. 1 and 2. The bolt-actu-

ating segment A, pivoted on the arbor B, attached to the side plate A', has a portion *a* of its periphery concentric with said arbor. Said portion *a* carries the projecting teeth or pins *a'* *a''* *a'''*. Said segment A has also the slot *a⁴* and the slot or notch *a⁴*, the slot *a³* being so placed as to receive the bolt-actuating pin *b* and the slot *a⁴* so as to receive the retaining-pin *c* of the detent or dog C when 60 said segment is in position against the stop D on the plate A', as shown in Fig. 1. Said segment A tends to assume this position under the pressure of the spring *d*, bearing against the projection *d'* on said segment A. 65 Said spring *d* is pivoted on the pin *d'*, attached to the side plate A', and bears against the pin *d''*, also attached to said side plate A'. Said segment A is preferably constructed in the manner indicated in the diagram Fig. 4, 70 75 in which the plates *a⁵ a⁶ a⁷ a⁸*, consisting of sheet-steel, brass, or other metal, are suitably fastened together and bear upon their cylindrical peripheries the teeth or pins marked *a⁹ a⁹* in said diagram. By thus employing 80 separable plates in the construction of the segments the toothed peripheries of said segments may be varied by varying the order in which the said plates are superimposed upon each other. By providing a few extra plates 85 and combining them variously composite segments having a great variety of toothed peripheries may be obtained. By employing teeth of suitable shape the plates *a⁵ a⁶ a⁷ a⁸* may be formed by stamping, thus minimizing the cost of manufacture. The detent C, 90 preferably of sheet metal, consists of an arm C', pivoted on the pin *c'* and having at its free extremity the branches *c²* and *c³*. Said branch *c²* carries the above-mentioned pin *c*, and the branch *c³* carries the pin *c⁴*, adapted to bear against the segment A. The spring *c⁵*, which 95 is pivoted on the pin *c⁶* and is further held in position by the pin *c⁷*, bears at its free extremity against the detent C, giving said detent a tendency to approach the segment A. Said pins *c⁶* and *c⁷* are attached to the side plate A'. The segment E, pivoted on the arbor E' on the plate A', is similar in its construction to the segment A, having the pins 100 or teeth *e' e² e³* projecting from the cylindrical portion *e* of the periphery of said segments.

Said portion e is concentric with the arbor E' . Said segments A and E are preferably so relatively placed that their planes of rotation are parallel and the adjacent parts of their circular portions a and e curve in opposite directions. The teeth of one of said segments preferably alternate with the teeth of the other when said segments are properly rotated; but said segments are so constructed 5 that neither one of said segments can cause the rotation of the other of said segments. The spring F, which is pivoted upon the pin f' , attached to the side plate A', bears against the arbor E' and also bears against the segment E in such a manner as to cause said segment to assume a position against the stop f , as shown in Fig. 1. The segment E has a portion G of its periphery concentric with the arbor E' . Said portion G terminates at the 10 slot g in said segment. At the side of the slot g opposite to said portion G the segment E has an extension or arm g' for engaging the pin c^4 of the detent C. Said portion G, together with the sides of the slot g , forms 15 a cam-surface whereon said pin c^4 travels. The segments A and E and the detent C are so constructed and arranged that when the segment E rests against the stop f on the plate A' the pin c of said detent is within the slot 20 a^4 of segment A and the pin c^4 of said detent is in contact with the portion G of segment E. When the said parts are in this position, the motion of said detent is prevented. The slot g is so located that when the segment E 25 is rotated the arm g' engages the pin c^4 , causing it to enter said slot and operate the detent C in such a manner as to withdraw the pin c from the slot a^4 of the segment A, thereby releasing said segment. The keyway H, 30 formed by the guides h , attached to the side plate A', is of just sufficient size to receive the key K without binding it. The position of said keyway is such that said key upon entering it will become tangential to the portion e of segment E and also to the portion a of segment A. The key K (shown in Fig. 35 5 and indicated in part by dotted lines in Fig. 2) consists of a strip k , of metal, terminating in the bow or head k' and having the slots k^2 and $k^3 k^3$. For convenience of description the slots k^2 , which are not circumferentially inclosed, are herein referred to as "notches," and the slots k^3 , circumferentially inclosed, as "perforations." When the segments A 40 and E are at rest against the stops D and f , respectively, the teeth or shoulders a' and e' of said segments lie in the keyway H. When said key K enters said keyway, the extremity k^4 of said key engages said teeth a' and e' and 45 causes said segments to rotate. This brings the teeth $a^2 a^2$ and $e^2 e^2$ into the keyway H. The notches $k^2 k^2$ and perforations $k^3 k^3$ occupy such positions and are of such configuration as to receive successively and in their proper 50 order the said teeth $a^2 a^2$ and $e^2 e^2$. Those of the teeth $a^2 a^2$ and $e^2 e^2$ passing adjacently to the lateral edges of the keyway H when the

segments are rotated will require notches k^2 in the key K, while the perforations k^3 of said key will engage those of said teeth which pass 70 non-adjacently to said lateral edges. The stop L on the plate A' extends across the keyway H and forms the inner extremity thereof. The bolt M is provided with an arm m , extending in the direction of the slot a^3 of the 75 segment A and carrying the pin b . Said pin b is engaged within the slot a^3 of the segment A in such a manner that the rotation of said segment causes said bolt M to slide within the guides $m' m' m' m'$, attached to the plate 80 A'. The lip m^2 of said bolt forms a catch for the corresponding lip n of the bow N of the padlock. Said bow N is hinged on the pin n' on the plate A' and has at its hinged extremity the extension n^2 , said extension being 85 circular and concentric with said pin n' . Said circular extension n^2 is so formed upon the bow N that when the bolt M is retracted and said bow is raised said extension n^2 assumes a position behind said bolt M in such a manner as to hold said bolt in a retracted position, as shown in Fig. 2. The spring n^3 is pivoted on the pin n^4 , attached to the side plate A', and is held in proper position by the pin n^5 , also attached to the side plate A'. 90 Said spring n^3 bears against the extension n^2 of the bow N in such a manner as to raise said bow when the bolt M is retracted. 95

In the operation of the mechanism of said padlock when the segments A and E are at 100 rest against the stops D and f , respectively, as shown in Fig. 1, the pin c of the detent C is engaged within the slot a^4 of the segment A, and said segment is thereby rendered immovable. The withdrawal of the detent C 105 from the last-described position is prevented by the pin c^4 , which bears against the cylindrical portion G of the segment E. When inserted into the keyway H, the extremity k^4 of the key K strikes the tooth e' of segment 110 E and causes said segment to rotate in such a direction that the slot g and arm g' thereof approach the pin c^4 of the detent C; but as the portion G of said segment E is concentric with the arbor E' the motion of the detent C 115 is prevented until the slot g reaches a position opposite to the said pin c^4 . At this point the arm g' engages said pin, thereby causing it to simultaneously enter said slot and move the detent C on its arbor c' in such a manner as to withdraw the pin c of said detent from the slot a^4 of the segment A. The parts 120 of the mechanism are so correlated that the pin c is not withdrawn from said slot a^4 until immediately before the entering key K reaches the tooth a' of segment A. The said segment is thus released and may be rotated by said key. The teeth $e^2 e^2$ and $a^2 a^2$ enter the path of the key as their respective segments are rotated, and as the key occupies substantially the entire cross-section of the keyway H said teeth move laterally into the notches k^2 and perforations k^3 , provided in said key. 130 The motion of the key is limited by the stop

L. When the segment A is rotated, as described, the pin b, engaged within the slot a^3 of said segment A, is moved in such a manner as to retract the bolt M and withdraw the lip m^3 thereof from the lip n of the bow N. When the said bow N, thus released, is thrown back by means of the spring n^3 or otherwise, as shown in Fig. 2, the circular extension n^2 of said bow assumes a position 10 behind the bolt M and holds said bolt in a retracted position. As the bolt-pin b is securely fastened to the extension m of the bolt M and has practically no lateral play in the slot a^3 of the segment A, said bolt cannot be 15 moved independently of said segment. Therefore when the bolt M is cast it cannot be retracted by a force exerted directly against said bolt nor against said segment A, nor can said segment be released by pressure exerted 20 directly against the detent C. If the key is not employed, the bolt cannot be retracted except by the exertion of two separate forces acting simultaneously to rotate the segments A and E of the mechanism.

25 I will now describe my invention as applied to a bolt-lock, an example of which is shown in Figs. 3, 8, and 9 in the drawings. In this lock there are employed the same segment E, arbor E', stop f, detent C, detent-30 arbor c', and detent-spring c⁵ as in the padlock above described. The oblong bottom plate A² corresponds to the side plate A' and the spring F' to the spring F in said padlock. Said spring F' is pivoted on the pin f², attached to the plate A², and is held in position by the pin f³, also attached to said plate A². The segment O in said bolt-lock corresponds to the segment A in Figs. 1 and 2 and is pivoted on the arbor B', attached to the 35 bottom plate A². Said segment O has projecting from its cylindrical portion o the tooth or shoulder o' and the teeth o² o³ for engagement with the key K. Said segment O has also the slot o³ and the slot or notch o⁴, the slot o³ being so placed as to receive the 40 pin p, attached to the slide P, and the slot o⁴ so as to receive the pin c of the detent C when said segment is in position against the stop D', attached to the plate A². The spring 45 d⁴, held in position by the pivot d⁵ on the plate A² and by the pin d⁶, also on said plate, bears against the segment O and tends to hold said segment against said stop D'. The segments O and E and the detent C are so 50 constructed and arranged that when the segment E rests against the stop f on the plate A² the pin c of the said detent is within the slot o⁴ of the segment O and the pin c⁴ of said detent is in contact with the portion G 55 of the segment E. The keyway H', formed by the guides h' h', attached to the side plate A², is similar in construction and purpose to the keyway H in Figs. 1 and 2. When the segments O and E are at rest against the stops D' 60 and f, respectively, the teeth or shoulders o' and e' of said segments lie in the keyway H'. The stop L' on the plate A² extends across the

inner extremity of the keyway H' and is for the purpose of limiting the motion of the key K. The bolt M' has its outer or projecting 70 extremity m³ beveled and slides within the guides m⁴ m⁴ m⁴ m⁴, attached to the plate A². The spring R is pivoted on the pin r, attached to the plate A², and is held in position by the pin r', also attached to said plate A². Said 75 spring R bears against the inner extremity m⁵ of the bolt M' and has a tendency to shoot or cast said bolt. Said bolt M' has in the lower face thereof an L-shaped chamber or slot S, forming a slideway for the slide P. Said 80 slideway S is so proportioned that said slide P may travel therein a distance equal to the travel of the bolt M'. Said slide P is also L-shaped and slides freely within said slideway P in the direction of motion of the bolt M'. 85 Said slide is provided with the above-mentioned pin p, adapted to be engaged within the slot o³ of the segment O. The said slideway S occupies such a position in the bolt M' and the slide P is so formed that when 90 said pin p is engaged within said slot o³, if the segment O is at rest against the stop D' and said bolt M' is cast, then said slide will lie at the inner extremity s of the slideway S. When said slide P is free to move 95 in said slideway S, said bolt M' may be forced into the lock without moving said segment O; but the rotation of said segment in a direction away from the stop D' will retract said bolt. This construction furnishes the 100 action of the ordinary spring-lock, in which the bolt may be forced into the lock either by pressure exerted directly upon the bolt or by means of the key. The slide P has two indentations or sockets p' and p² for receiving the inner extremity of the threaded spindle T, the socket p² being nearer the inner extremity p³ of the said slide. Said 105 sockets are so placed that the socket p' may receive the spindle T when said slide is at 110 the inner extremity s of the slideway S, as shown in Figs. 3, 6, and 8, and the socket p² may receive said spindle when said slide P is at the opposite extremity of said slideway S, as shown in Fig. 9. Said bolt M' has a 115 threaded aperture t, communicating with the slideway S and receiving the threaded spindle T. Said spindle T extends through a slot (not shown) of suitable length in the lock-casing and has at its outer extremity a 120 milled head t' for convenience of operation. Said spindle T furnishes means whereby the bolt M' may be moved when the slide P is free to move in said slideway S. When said 125 spindle T is screwed into either of said sockets p' or p² or against any portion of the slide P, said slide cannot travel within the slideway S in the bolt M', but is fixed relatively to said bolt M'.

In the said bolt-lock shown in Figs. 3, 8, 130 and 9 the operation of the segment E and detent C is the same as the operation of the same parts shown in Figs. 1 and 2 and the operation of the segment O is similar to the

operation of the corresponding segment A in Figs. 1 and 2. When the segment O is rotated by means of the key in the manner described the slide P, having its pin p engaged within the slot o^3 of said segment, is caused to move toward the inner extremity s of the slideway S in the bolt M'; but as the slide P occupies a position at the inner extremity s of the slideway S when said bolt is cast, said motion of the slide P will be communicated to said bolt M' and cause the retraction of said bolt whether said slide is free to move in said slideway or not. By screwing the spindle T into the socket p' the bolt M' and slide P become relatively fixed and said bolt may be retracted by the key, but cannot in any other way be forced into a retracted position. It will thus be seen that when so desired the bolt-operating mechanism may be so set that the bolt M' is immovable as regards a force exterior to the lock or any force applied directly to said bolt, but is at the same time operative by means of the key. This is an important advantage, as locks are often operated by unauthorized persons by prying the bolt—as, for example, in an ordinary spring door-lock, by inserting a tool between the edge of the door and door-casing and pressing said tool against the beveled extremity of the bolt. Such forcing of the bolt is impossible in a lock employing the mechanism hereinabove described. When the spindle T is not in contact with the slide P, said slide is free to move in the slideway S, and the bolt M' may be retracted independently of the segment O either by means of said spindle T or by a force exterior to the lock properly exerted upon said bolt. When such retracting force is withdrawn, the bolt M' is cast by the spring R, as in the ordinary spring-lock. If the spindle T is screwed into the socket p^2 of the slide P at a time when the bolt M' is retracted and the segment O lies against the stop D', as shown in Fig. 9, said bolt will remain in a retracted position.

Referring in general to both forms of locks described and shown, if an attempt be made to insert into the keyway of the lock an object not properly notched and perforated the teeth of the segments will wedge against such object, and their motion and the motion of the entering object will be arrested. In order to prevent the insertion of such objects, it is preferable to make the key as thin as consistent with necessary strength and the keyway correspondingly narrow. It is preferable to have those of the teeth which lie nearest to the teeth e' and a' or o' enter into the keyway immediately upon the rotation of their respective segments. It is also desirable to have the teeth upon the segments as frequent as may be without unduly weakening the key by reason of the required notches and perforations. By reference to the drawings it is evident that when the segments are rotated the teeth successively approach and recede from the keyway H and that at no one

time are all of said teeth in said keyway. The teeth e' and a' or o' are the only ones in such position when the bolt is cast, and said teeth are the first to recede from said keyway when the segments are rotated. It is evident, therefore, that if a wire could be inserted into the keyway in such a manner as to avoid the succeeding teeth, said wire would tend to slip away from the first tooth e' on account of said recession and the increasing obliquity of the face of said tooth. This is true also of the tooth a' or o' . Therefore it is necessary to engage succeeding teeth of each segment in order to retract the bolt. When the lock is operated by the key, the teeth of the segments will make contact with substantially uniform force upon the portions of said perforations and notches lying nearest to the same extremity of the key. For this reason the wear upon the said portions lying nearest to the same extremity of the key will be uniform, and the respective distances between said portions of said perforations and notches will remain constant. The key will therefore be substantially unaffected by wear in so far as its ability to operate said lock is concerned.

It is evident that certain modifications in the form of various parts of the lock may be made without departing from my invention. For example, the angular extent of the cylindrical tooth-bearing portions of the segments may be increased, while the diameter of said cylindrical portions may be decreased until the segments become substantially cylinders suitably toothed and notched. In such case the lock will be more compact than when the diameter of the segments is greater. Also, the stops L and L' may be omitted to permit the extremity k^4 of the key to pass through and beyond the lock. While the detent C shown in the lock is a valuable and novel part thereof, still I do not limit myself to a lock having such detent. The detent, or both the detent and the detent-actuating segment, may be altogether omitted and the broad features of my invention still remain.

What I claim as new, and desire to secure by Letters Patent, is—

1. In a key-operated lock, two pivoted segments located upon opposite sides of the keyway thereof, and bearing upon their peripheries teeth or pins for engagement with the key and for preventing the insertion of foreign objects into said lock; in combination with a bolt, sliding within suitable guides and operated by one of said segments.

2. In a lock, the combination of a sliding bolt, a toothed pivoted segment for operating said bolt, a detent for engaging and releasing said segment, means for operating said segment, and means for operating said detent.

3. In a key-operated lock having pivoted segments bearing upon their peripheries pins or teeth for engagement with the key, the combination of a detent, a cam upon one of

said segments for operating said detent, and locking parts operated by the other of said segments.

4. In a lock operated by the thrust of a key 5 thereinto, the combination of a detent forming one of the component parts of said lock, a sliding bolt, pivoted segments whereof one actuates said bolt, and another operates said detent, and means for operating said seg- 10 ments.

5. In a key-operated, bolt-actuating mechanism, the combination of a sliding bolt; two pivoted segments lying on opposite sides of 15 the keyway of said mechanism, one of said segments having means for actuating said bolt and having means for engagement with a detent; a cam upon the other of said segments whereby said detent may be held in engagement with said first-mentioned seg- 20 ment, unless retracted therefrom by means of said second segment; and teeth or pins upon said segment for engagement with the operating-key.

6. In a key-operated lock, the combination 25 of a bolt; a pivoted segment for actuating said bolt; a detent acting upon said segment;

a second pivoted segment for operating said detent; a keyway tangential to both said segments at the cylindrical portions thereof, and pins or teeth upon the cylindrical portions of 30 said segments, said pins or teeth entering and receding from said keyway as said segments are rotated.

7. In a key-operated lock, the combination of a locking-bolt; a pivoted segment having 35 a toothed cylindrical surface and acting upon said bolt; said segment having a slot therein for receiving a portion of a detent; a pivoted detent having a portion for entering said slot in said segment, and another portion for trav- 40 eling upon the cam-surface of a second seg- ment, and for entering a slot in said second segment; a second pivoted segment having a cam-surface to act upon the adjacent arm of 45 said detent; said second segment having a toothed cylindrical surface, and both of said segments being operated by the engagement of the teeth of said segments with a key.

ABRAHAM L. MACMASTER.
